ABSTRACT OF THE DISCLOSURE

A non-inductive resistor structure for the parallel resistor in an oil circuit breaker in which individual resistor coil layers are wound above one another and are clamped together by a central insulation rod. Each coil layer is disposed between spacer plates which are slotted to permit passage of a continuous resistance wire from coil to coil with adjacent wire coil layers being wound in opposite directions.

This application is a division of copending application Ser. No. 439,304, filed Mar. 12, 1965, now U.S. Pat. 3,392,248, in the name of Earl B. Rietz et al., entitled Interrupter Structure Having Contoured Arc Splitter Plates and Separately Housed Resistor Contacts and Resistor Structure Therefor, and assigned to the assignee of the present invention.

This invention relates to oil circuit breakers, and more specifically relates to a resistor which is to be connected in parallel with the interrupter structure of an oil circuit breaker.

The object of this invention is to provide an improved resistor structure for use with circuit interrupters.

Another important object of this invention is to provide a novel arrangement for these resistors wherein resistor coil layers are wound above one another and are clamped together by a central insulation rod.

Another object of this invention is to provide a novel pancake resistor arrangement which provides easily accessible electrical connections at each end thereof.

A further object of this invention is to provide a novel structural arrangement for a pancake resistor which permits heat expansion of the unit and prevents free entrance of carbon into the unit.

A still further object of this invention is to provide a novel pancake resistor structure which may be easily assembled.

In the performance of resistors for interrupter structures, it is preferable to use a non-inductive resistor. Such resistors are commonly formed by winding the layers of resistance wire in alternate directions.

It is a further important object of this invention to provide a novel structure for permitting the simplified manufacture of a non-inductive resistor having layers of resistance wire wound in alternate directions.

A further object of this invention is to provide a novel non-inductive resistance structure.

These and other objects of this invention will become apparent from the following description when taken in connection with the drawings, in which:

FIG. 1 shows a top plan view of an interrupter structure and the housing for its parallel connected resistor.

FIG. 2 is a cross-sectional view, similar to FIG. 1, and illustrates the connection of the resistor to the interrupter.

FIG. 3 is a cross-sectional view of FIG. 2 taken across

the lines 3—3 in FIG. 2, and particularly illustrates a novel resistor mounting structure of the invention.

FIG. 4 is a side view of the resistor structure to illustrate the manner in which the resistor wire is non-inductively wound.

5 FIG. 5 is a plan view of the resistor of FIG. 4 seen from the left-hand side.

FIG. 6 is a plan view of the resistor of FIG. 4 seen from the right-hand side.

10 FIG. 7 is an exploded perspective view schematically illustrating the manner in which the plates permit simple non-inductive winding of the resistance wire.

FIG. 8 schematically illustrates the winding of the first layer of resistance wire.

15 FIG. 9 schematically illustrates the winding of the second layer of resistance wire.

FIG. 10 schematically illustrates the winding of the third layer of resistance wire.

20 FIG. 11 schematically illustrates the winding of a fourth layer of resistance wire.

FIG. 12 shows various elements *a* to *r* in the order in which they are stacked for the novel resistor structure.

Referring first to FIGS. 1 and 2, the novel resistor is shown with an interrupting chamber structure.

25 As shown in FIGS. 1 and 2, the complete structure will be supported from an upper conductive casting 30 which can be suitably secured to the end of an electrical bushing. This electrical bushing extends through the main support tank (not shown) which contains oil in which the complete interrupter structure is immersed.

30 The interrupter includes an insulation casing 31 which is suitably connected to the casting 30.

FIGS. 1, 2 and 3 additionally show a novel resistor structure which can be used as the parallel connected impedance member for an interrupter. More specifically, 35 a resistor structure generally shown by numeral 180 in FIG. 1 is suitably secured to the interrupter structure of FIG. 1 with the upper terminal of the resistor connected to member 30, and the lower terminal of the resistor connected to the resistor contacts 151 and 152 in the interrupter unit.

40 This resistor structure is formed in the novel manner particularly shown in FIG. 3, and includes a stack of resistor elements 181, which will be described more fully hereinafter, which are contained within an insulation tube 182. The tube 182 receives a plate 183 which may be metallic which is prevented from moving upwardly by means of a split interference ring 184 contained in a suitable groove in casing 182. An upper conductive housing or support 185 is then connected to plate 183 by suitable screws such as screws 186 and 187 (FIGS. 1 and 3).

45 The upper housing section 185 has an upwardly extending flange section 187a (FIGS. 1 and 3) which receives bolts such as bolts 188 which serve to bolt the support member 185 directly to suitable portions of upper member 30 of the interrupter structure.

50 The lower portion of the resistor structure of FIG. 3 includes a lower plate 189 which bears against the bottom of the resistor stack 181 and which is prevented from moving out of the tube by a suitable split interference ring 190. The bottom of casing 182 is then received by a suitable conductive support 191 which, as best shown in FIG. 2, is secured to the bottom of the interrupter housing by screws 160 and 162 which further serve to electrically engage the resistor contacts 151 and 152.

55 In order to hold the resistor stack 181 together during assembly, a wooden rod or other suitable insulation rod 200 extends through the complete resistor housing and is terminated at either end by nuts 201 and 202 respectively. The plate 189 then seats atop a spring 203 which externally surrounds the lower end of rod 200 and its lower nut 202. At the upper portion of the struc-

70

ture, a pressure plate 204 bears atop stack 181 and receives a compression spring 205 which has its other end in engagement with the plate 206 which is carried within a suitable aperture in upper housing portion 185.

This novel structural arrangement permits the rod 200 to be in tension only during assembly of the device and removes any support function from the rod 200. The complete support for the resistor structure comes from the casing 182 and its upper and lower supports 185 and 191.

In order to assemble this novel structure, the resistor pack 181 is first inserted into the tube 182; the plate 183 and its interference ring 184 and the support 185 having been previously assembled in a loose manner by the screws 186 and 187. This permits the lower split interference ring 190 to be inserted into tube 182. The screws such as screw 186 are then tightened, which pulls the support 185 downwardly and into engagement with the upper end of tube 182. At the same time, spring 205 is compressed, and forces the resistor stack 181 downwardly until plate 189 engages interference ring 190.

Accordingly, the structural mounting, as indicated previously, completely relieves the wooden insulating rod 200 from the strong mechanical forces, as would occur during a short circuit interruption operation.

The electrical circuit for the system partly extends from housing 191 which is appropriately connected to the terminal 220 through plate 189 and spring 203. Note that the terminal 220 could be connected to the resistor contacts 151 and 152 in any desired manner other than through the housing section 191.

The upper end of the resistor pack terminates in terminal 221 which, by making plate 204 of metallic material, is electrically connected through spring 205 and metallic plate 206 to the metallic upper housing 185 and thence to the upper conductive housing 30 of the interrupter.

In order to permit oil circulation through the resistor structure, bottom slots such as slot 225 are provided in the lower plate 189 and through openings 226, 227 and 228. Note that the uppermost opening 228 is so arranged in the side of upper housing 185 that carbon and other similar impurities floating in the circuit breaker oil will not easily settle into the resistor structure.

The main purpose of nut 201 is to hold the resistor pack together when it is removed from the tube 181. Thus, the complete resistor pack, along with plates 189, 204, 183 and 206, serve as a subassembly of the resistor structure.

It is to be particularly noted that prior art resistor devices utilize the central rod 200 as the main structural member for carrying the resistor structure from the interrupter. Thus, the rod necessarily becomes very large which, in turn, enlarges the complete unit.

The manner in which the resistor package 181 is formed is particularly shown in FIGS. 4 to 11. The assembly of the resistor of FIGS. 4 to 11 will be recognized as the resistor structure removed from its housing 182 in FIG. 3. Note particularly that the spring 203 is captured by lower nut 202 by means of a square sheet 250 of FIGS. 4 and 5 whose corners are folded over, as shown in FIG. 5, to capture spring 203.

It is extremely desirable that the resistor used as the parallel impedance for the interrupter of the invention or of other similar interrupter equipment be of a non-inductive nature. Non-inductive resistors are generally well known, and are formed by winding a resistance wire in several layers with alternate layers, for example, being wound in opposite directions. In this manner, the magnetic fields induced in adjacent layers oppose one another so that the inductance of the coil is negligibly small.

Present arrangements for achieving the opposite winding direction for alternate layers of resistance wire are extremely awkward, time consuming, and the wire can-

not be wound directly from a wire spool. The novel resistor structure shown in FIGS. 4 to 11 is one in which a non-inductive resistor can be wound directly from a wire spool with the coils or adjacent layers being suitably separated to keep creep voltage stress for between-layer cross-overs below a safe maximum value.

In accordance with the invention, each layer of resistance wire is associated with a set of spacers and plates wherein the spacers and plates have suitable notches therein for permitting placement and winding reversal of the resistor wire which is wound from a single spool. Moreover, the spacers and plates for adjacent layers are 90° displaced from one another which permits a similar displacement at the between-layer cross-over to keep voltage creep stresses to a minimum.

In FIGS. 4 and 8 to 11, there is illustrated the formation of the first four layers of the resistor, it being understood that the complete resistor will be formed in an identical manner.

Referring now to FIG. 4, there is shown four groups 260, 261, 262, and 263 respectively of three plates and a winding plate each. The groups 260 through 263 are shown in FIGS. 8 to 11 respectively. Each of the stacks 260 through 263 formed of plates, best shown in FIG. 7 for the case of stacks 260 and 261 in exploded perspective view.

The individual plates of stacks 260 through 263 are further shown in FIG. 12 as elements *a* to *r*, which are in the order in which the plates are stacked. Each of the 30 plates are mounted on the square wooden shaft 200. The group of plates 260 is shown in FIG. 12 as elements *a*, *b*, *c* and *d*, and includes winding plate 270, first and second slotted plates 271 and 272, which are identical in construction and contain narrow slots 273 and 274 respectively, and notches 276 and 277 respectively, and a central plate 278 which contains a V-shaped notch 279.

Each of the remaining groups are made up of similar plates to those shown in FIG. 12, elements *a*, *b*, *c* and *d*, but are rotated clockwise by 90° with respect to the plates 40 of an adjacent group. This feature permits applicant's novel displaced cross-over point in the resistance winding.

The method of winding the non-inductive resistor of the invention when using plates of the type shown in FIGS. 4 to 12 is best understood from FIG. 7 for the case of the first two groups 260 and 261.

Referring particularly to FIG. 7, the resistance wire 290 is taken from some suitable spool, not shown. The various plates such as plates 271, 278, 272 and 270 are then contained on the square wooden shaft 200 and the resistance wire 290 is placed in the groove 276 of plate 271. This wire is then brought to the top of the sloping portion of V-shaped slot 279 and then rides down to the slot at the bottom thereof. At this point, the wire extends over to the bottom of the narrow slot 274 and thence to the top surface of the winding plate or disk 270. The wooden shaft 200 is then rotated so that the resistance wire winds on plate 270 in the direction shown by the arrow 291. Some predetermined number of turns are then formed on the plate 270 to form a pancake-type resistance winding 292.

The next group of plates 261 have been assembled and are rotated by 90° with respect to the similar stack of plates 270. The end of pancake winding 292 is taken from a point to the rear of the winding in FIG. 7, and 65 is bent directly over into the notch 276a of plate 271a of group 261.

In a manner identical to that for group 260, the wire then enters the V-shaped slot 279a of plate 278a to the bottom of the slot and then over through the bottom of slot 274a of plate 272a. Thereafter, the wire is placed immediately on the winding surface of plate 270a and the assembly is rotated in such a direction that a pancake resistance winding 294 is formed with the wire winding in the direction of the arrow 293. Note that winding 294 is wound oppositely to winding 292, whereby the magnetic

fields generated by each of the windings when current flow passes therethrough are in opposing directions, thus rendering these two winding sections relatively non-inductive.

Clearly, this winding process continues until the end of the resistor is reached with the adjacent windings being wound oppositely from one another. Moreover, the points at which each of the windings terminates and crosses over to the next group of plates are displaced with respect to one another by 90°, thereby improving the voltage distribution across the winding.

Although this invention has been described with respect to its preferred embodiments, many variations and modifications will now be obvious to those skilled in the art, and it is preferred, therefore, that the scope of the invention be limited not by the specific disclosure herein but only by the appended claims.

The embodiments of the invention in which an exclusive privilege or property is claimed are defined as follows:

1. A non-inductive resistor comprising a plurality of spaced pancake windings of a continuous resistance wire and a plurality of sets of spacer plates between said windings; each of said sets of plates including a first plate having an off-center slot therein extending from the periphery thereof, a second plate having a notch in the periphery thereof, and a central plate interposed between said first and second plates having a pie-shaped slot extending from the periphery thereof; the bottom of said pie-shaped slot in said central plate being adjacent the

bottom of said off-center slot in said first plate; one side of the beginning of said pie-shaped slot in said central plate being adjacent said notch in said second plate; said resistance wire extending across said notch, along one side of said pie-shaped notch and through the bottom of said off-center slot in passing from one pancake winding to an adjacent pancake winding; adjacent pancake windings being wound in opposite directions.

2. The device substantially as set forth in claim 1 wherein said off-center slots of each of said sets of adjacent plates are rotated with respect to one another by a predetermined angle.

3. The device substantially as set forth in claim 1 wherein each of said first and second plates include both said notch and said off-center slot whereby said first and second plates are identical.
